CONTROL CIRCUIT

William A. Ray, Glendale, Calif.

Application August 9, 1937, Serial No. 158,126

6 Claims. (Cl. 236—46)

My invention relates to electrical control circuits and has for its chief object the provision of an improved circuit whereby electric devices may be applied to influence circuit-opening-and-closing control apparatus connecting a source of electrical power, without the requirement of additional power supply wires for said electric devices.

A particular object of my invention is the provision of an improved electrical circuit for connecting an electric-motor-operated time-delay device designed to influence circuit-opening-and-closing apparatus for controlling physical conditions, such as temperature, humidity, etc., without the requirement of power supply wiring in addition to that leading to said control apparatus.

Other objects and advantages will be apparent during the course of the following description.

Referring to the drawing:

Figure 1 is a diagrammatic view showing my invention applied to a conventional "2-wire" thermostat circuit; and

Figure 2 is a similar view showing my invention applied to a conventional "3-wire" thermostat circuit.

Referring more particularly to Fig. 1 of the drawing, the numeral 11 denotes a thermostatic element of conventional bi-metal construction carrying the contact 12 and capable of movement on decrease of temperature to cause coaction between said contact 12 and the fixed contact 13. A switch 14, preferably having snap-action (not shown), having a moving arm 15 designed to coact with either of the fixed contacts 16—17 and having manual operating means, as by the knob 18. 19 denotes an electric motor having a driven shaft 20 to which is adjustably attached the operating arm 21 as by the thumb screw 22 and designed to cooperate with the extension arm 23 of the switch 14. The manually operable cam 24 is adapted to hold the arm 15 away from the contact 16 to open the circuit for purposes that will be explained later. Extended, as shown by the broken lines, are the designated connections for a source of electrical power and a load.

Referring now to Fig. 2 of the drawing, the numeral 25 denotes a bi-metallic thermostatic element carrying a contact 26 and capable of movement on decrease of temperature to cause coaction between said contact 26 and the fixed contact 27. Attached to the element 25 is a flexible extension 28 carrying a contact 29 engageable with the fixed contact 30. The switch

14 and the motor 19 and their associated parts are identical with those shown in Fig. 1. Extended, as shown by the broken lines, are the designated connections for a source of electrical power and a load, in the form of a relay 31 having a winding 32, a core 33 and an armature 34 engageable with the fixed contact 35. Arranged to move with the armature 34, but insulated therefrom, is another armature 36 engageable with the fixed contact 37, affording means for switching power to a load device.

Referring again to Fig. 1, it will be seen that the thermostat is connected through the switch arm 15 when it is in the "on" position to complete the power circuit to the load. On decrease of temperature, the thermostat contacts 12—13 close and the load is energized. The said load may be an electrically operated gas valve for a heating system, motor furnace operator, or similar device. It is usually undesirable to operate the heating system during the night so the switch is turned to the "off" position, rendering the thermostat contacts inoperative to complete the circuit to the load.

In this position of the switch the power circuit to the motor 19 is complete through the "off" contact, the switch arm and the load device. The impedance of the motor may be high in relation to that of the load, so sufficient power is passed through the load to operate the motor. But, for the same reason, insufficient power is passed through the motor to operate the load device.

The timing arm 21 of the motor is arranged to make one complete revolution in, say, 12 hours. So any time delay less than 12 hours may be arranged as desired by adjusting the starting position of the timing arm 21 so that it will travel through some certain fraction of a revolution before it strikes the extension arm 23 to turn "on" the switch 14, when the heating system will be put into operation if the thermostat contacts are closed responsive to low temperature. At the same time the power circuit to the motor is opened. The switch 14 may preferably be of the snap-action type so that there is no appreciable time lapse in operating it between its on and off positions and so that the motor circuit will not be opened before the switch has completed its movement. The motor may preferably be of the synchronous-speed alternating current type.

If, at times, it is desired to render the heating system unresponsive to the thermostat for an indefinite length of time, the motor circuit

through the "off" position of the switch may be opened, as by rotating the cam 24 to hold the arm 15 away from the contact 16.

In Fig. 2 a different type of thermostat is shown, having a flexible contact-carrying extension arm 28 attached to and movable with the bi-metallic member 25 and arranged so that, on movement of the thermostat in response to decrease in temperature, circuit is first made through contacts 29 and 30 before it is made through the contacts 26 and 27. Likewise, on reverse movement of the thermostat, contacts 26 and 27 separate before contacts 29 and 30. In operation, presuming the switch 14 to be "on", when the contacts 29-30 close, no other action takes place. But when the thermostat moves further and closes contacts 26-27 in addition, the power may then flow from contact 17 through switch-arm 15, contacts 30-29, members 28 and 25, contacts 26-27 to complete the circuit through the relay winding 32. When thus energized, the armature 34 is attracted to complete its circuit through contact 35 which provides a "holding" circuit for the relay so that, on decrease of temperature, the relay does not become de-energized until the circuit is finally opened on separation of the contacts 29-30. The thermostat circuit shown in Fig. 2 is a conventional "3-wire" control circuit designed to provide a definite time lag between the energizing and de-energizing of the relay and no claim is made to it by me. My invention has been shown applied to the thermostat circuit by means of the switch 14, the motor 19 and their associated parts and the operation is similar to that described in reference to Fig. 1, the only difference being that in Fig. 2 the load, through which the circuit for the motor is completed, is definitely shown as a relay winding. The small amount of current passed by the motor through the relay winding is not sufficient to operate the relay. And likewise, the impedance of the relay winding, being low in respect to that of the motor, permits sufficient current to pass to operate the motor.

It will be seen that I have provided a control circuit that permits the addition of an electric-motor-operated timer to a thermostat circuit without the requirement of wiring in addition to that necessary for the thermostat control operation minus such a device. This is an important matter, as the controlled apparatus is usually far from the thermostat or thermostats and the running of one or two additional wires to each control position involves a considerable installation expense and possibility of misconnections. By my invention, a self-contained unit including a thermostat and an electric timer therefor may be installed as simply as a thermostat alone.

While I have shown my invention applied to conventional thermostat circuits, it will be readily understood that it may be in similar ways applied to other systems for controlling physical conditions, in which a circuit is opened and closed in response to variation in said conditions.

The particular apparatus shown is merely illustrative and modifications may be made therein.

I desire it to be understood that no limitation on the invention is intended than is imposed by the scope of the appended claims.

I claim as my invention:

1. In a control system, a first electric circuit including in series a source of power, a load, a switch comprising a member movable into alternative contact positions, and means responsive to change in physical conditions to control said load;

an electric time-delay device adapted to move said member into position to close said first circuit after a predetermined lapse of time; and a second electric circuit including in series said time-delay device, said load, said source of power, and said switch; said switch being adapted, in one position of said member, to close said first circuit and simultaneously to open said second circuit and, in the alternative position of said member, to open said first circuit and simultaneously to close said second circuit. 10

2. In a control system, a first electric circuit including in series a source of power, a load, a switch comprising a member movable into alternative contact positions, and means responsive to change in physical conditions to control said load; an electric time-delay device adapted to move said member into position to close said first circuit after a predetermined lapse of time; and a second electric circuit including in series said time-delay device, said load, said source of power, and said switch; said switch being adapted, in one position of said member, to close said first circuit and simultaneously to open said second circuit and, in the alternative position of said member, to open said first circuit and simultaneously to close said second circuit; said electric time-delay device having high impedance in respect to that of said load whereby insufficient power is passed by said device to operate said load. 30

3. In a control system, a first electric circuit including in series a source of power, a load, a switch comprising a member movable into alternative contact positions, and a thermostat to control said load; an electric time-delay device adapted to move said member into position to close said first circuit after a predetermined lapse of time; and a second electric circuit including in series said time-delay device, said load, said source of power, and said switch; said switch being adapted, in one position of said member, to close said first circuit and simultaneously to open said second circuit and, in the alternative position of said member, to open said first circuit and simultaneously to close said second circuit. 40

4. In a control system, a first electric circuit including in series a source of power, a load, a switch comprising a member movable into alternative contact positions, and a thermostat to control said load; an electric time-delay device adapted to move said member into position to close said first circuit after a predetermined lapse of time; and a second electric circuit including in series said time-delay device, said load, said source of power, and said switch; said switch being adapted, in one position of said member, to close said first circuit and simultaneously to open said second circuit and, in the alternative position of said member, to open said first circuit and simultaneously to close said second circuit. 50

5. In a control system, a first electric circuit including in series a source of power, a load, a switch comprising a member movable into alternative contact positions, and a thermostat to control said load; a synchronous electric-motor-operated time-delay device adapted to move said member into position to close said first circuit after a predetermined lapse of time; and a second electric circuit including in series said time-delay device, said load, said source of power, and 70

- said switch; said switch being adapted, in one position of said member, to close said first circuit and simultaneously to open said second circuit and, in the alternative position of said member, 5 to open said first circuit and simultaneously to close said second circuit; said synchronous electric motor having high impedance in respect to that of said load whereby insufficient power is passed by said device to operate said load.
- 10 6. In a control system, a first electric circuit including in series a source of power, a load, a switch comprising a member movable into alternative contact positions, and a thermostat to control said load; an electric time-delay device

adapted to move said member into position to close said first circuit after a predetermined lapse of time; a second electric circuit including in series said time-delay device, said load, said source of power, and said switch; said switch being 5 adapted, in one position of said member, to close said first circuit and simultaneously to open said second circuit and, in the alternative position of said member, to open said first circuit and simultaneously to close said second circuit; and 10 means for temporarily rendering said switch member inoperable to close said second circuit.

WILLIAM A. RAY.
